United States Patent Office.

ALFRED WEED, OF BOSTON, MASSACHUSETTS.

Letters Patent No. 68,585, dated September 3, 1867.

IMPROVEMENT IN FILE-HANDLES.

The Schedule referred to in these Letters Patent and making part of the same.

TO ALL WHOM IT MAY CONCERN:

Be it known that I, ALFRED WEED, of Boston, in the county of Suffolk, and State of Massachusetts, have invented an improved File-Holding Handle; and I do hereby declare that the following, taken in connection with the drawings which accompany and form part of this specification, is a description of my invention sufficient to enable those skilled in the art to practise it.

This invention is specially designed and adapted for holding in adjustable jaws, attached to a handle, such files as are constructed without a tang, and it consists in the peculiarities of the details of construction and arrangement of the metallic grasping jaws, and the parts therewith immediately connected.

Figure 1, of the drawings, is a longitudinal section taken through the centre of the handle, the jaws, and the file grasped thereby, while

Figures 2, 3, 4, and 5, show end views of the jaws, each respectively grasping a flat, a square, a triangular, and a round file.

a represents an ordinary handle, into which is driven the spindle *b*, this being formed integral with the shoulder *c* and fixed jaw *d*. The loose jaw *e* is provided with a screw, *f*, and nut, *g*, by means of which the loose jaw can be drawn toward the fixed jaw, and thus clamp any file which may be inserted between the jaws. The rear end of the loose jaw abuts against the front face of the shoulder *c*, and is thereby prevented from turning on the screw *f*, as a pivot, which, being located near the rear of the loose jaw, gives room in front of the screw for entering the rear end of the file. In both the fixed and loose jaws grooves are made, preferably corresponding to each other, and of the right-angular form shown, said grooves being adapted, as seen in figs. 3, 4, and 5, to firmly hold any file of the form of section shown in said figures, while flat and half round files are held firmly between the parallel faces of the jaws, there being at the rear end of such forms of files a notch which fits upon the screw between the jaws, and thus practically prevents lateral movement of the files.

With three of these handles, one large, one medium, and one small, a machinist may make use of a large assortment of files.

To render the holding of files between the jaws of my improved handle still more certainly immovable, one of the jaws, preferably the fixed one, may be constructed with a rib on its face, as seen at *h*, corresponding grooves being made in the flat files to be held.

I claim a tool-holding handle, as made with jaws, arranged to have an adjustment with respect to each other, one or both of which are provided with a transverse rib or ribs, and a longitudinal groove or grooves, constructed substantially as described.

ALFRED WEED.
